CRIMPING TOOL

Henry W. Demler, Lebanon, Pa., assignor to
AMP Incorporated, Harrisburg, Pa.

Application August 7, 1957, Serial No. 47,256

Term of patent 14 years

(Cl. D54—13)

Fig 2

Figure 1 is a perspective view of a crimping tool embodying my new design, shown in the closed position.

Figure 2 is a view similar to Figure 1 showing the crimping tool in the open position.

The appearance of the device as viewed from the opposite side is substantially identical to that shown in Figures 1 and 2.

I claim:

The ornamental design for a crimping tool, substantially as shown and described.
